UNITED STATES PATENT OFFICE.

WILLIAM M. FREEDMAN, OF BROOKLYN, NEW YORK, ASSIGNOR TO SELL-BEST NOVELTY CANDY CO. INC., OF BROOKLYN, NEW YORK, A CORPORATION OF NEW YORK.

BOX.

Application filed December 9, 1925. Serial No. 74,228.

This invention relates to a box or receptacle made of cardboard or similar suitable material and designed to contain candy and a prize package or other device, and is so 5 constructed and adapted to be worn by a child or other purchaser as a toy wrist watch.

In carrying out the invention, the article made in accordance therewith preferably 10 comprises a body having parts folded to form a receptacle for the goods and readily opened to obtain or examine the goods, together with extension straps from the sides or ends of the body of the container to be 15 passed around the wrist or arm and to be connected so that the articles may be thus carried and the device used as a toy wrist watch.

The invention will be more particularly 20 described in conjunction with the accompanying drawings in which

Figure 1 is a perspective view of the improved box.

Fig. 2 is a section on line 2—2, Fig. 1, 25 showing in dotted lines the strap extensions adapted to pass around the wrist, and

Fig. 3 is a blank from which the box or container is formed.

In carrying out the invention, the box 30 or container is preferably formed from a suitably shaped blank as illustrated in Fig. 3. In this blank the box or container, side walls, end flaps and extension straps are all provided for in an integral structure, 35 and is preferably made of suitable paper, cardboard, or similar material. The box or container preferably comprises a base or bottom member 10 having at one side a side extension 11 and end flap 12, the extent of 40 which is determined by score lines as indicated in Fig. 3. At the opposite side and also determined by suitable score lines, there is an extension providing for a side member 13 corresponding to the side member 11, 45 and a top member 14. The ends of the top member 14 are also extended and provided with suitable score lines to form an end member 15 and flap 16, and a corresponding end member 17 and flap member 18. On the 50 outer face of the top or cover 14 there may be printed the representation of a watch or clock as indicated at 19 in Fig. 1.

At the ends thereof, the base or body member 10 is provided with extensions 20 and

21. In the extension 20 adjacent the end 55 thereof, there is a transverse slot 22 and the extremity of the extension 21 is preferably rounded as indicated at 23 and the edges thereof notched as indicated at 24 and 25. 60

In setting up the box from the blank as hereinbefore described, the parts are folded on the score lines and the end flap 12 secured to the inner surface of the adjacent portion of the top or cover member 14 by a suitable 65 adhesive or otherwise, and the end members 15 and 17 turned to position and the box formed and closed by inserting the flaps 16 and 18, which as will be understood may be readily opened to examine or obtain the 70 contents of the box thus formed. It will also be understood that the bottom, sides, ends, and if desirable, both surfaces of the straps, 75 may be printed with representations of diverse objects, advertising matter or otherwise. In the use of the box the straps 20 and 21 may be passed around the wrist and the end 23 of the strap 21 passed through the slot 22 in the strap 20 so that the notches 24 and 25 in the strap 21 engage the extremities 22 in the strap 20 to secure the box in 80 position on the wrist or arm so that in this use the article may be employed as a toy wrist watch and at the same time forms a 85 container in which the candy or other merchandise may be carried on the arm.

I claim as my invention:

1. A box or container formed from a blank comprising a bottom wall, straps extending from the oppositely disposed portions of the bottom wall, a side wall extending from another side portion of the bottom wall, a side wall extending from the bottom wall in a position oppositely disposed to the aforesaid side wall, a top wall, end walls 90 extending from the said top wall, and flaps extending from the said end walls and adapted to cooperate with the same and the said bottom wall to close the ends of the box, the said straps being adapted to pass 95 around the wrist and to be connected to each other to secure the box in position on the wrist.

2. A box or container made from a blank of paper material comprising a bottom wall, 100 straps extending from oppositely disposed portions of the said bottom wall, a side wall extending from the bottom wall substantially

tially parallel to the said straps, a top wall extending from the said side wall, end walls extending from the said top wall, flaps extending from the end walls, a second side wall extending from the bottom wall in a position oppositely disposed to that from which the first aforesaid side wall extends, and a connecting flap extending from the said second side wall and adapted to be con-

nected to the top wall to form the body of the box, the said flaps extending from the end walls being adapted to be turned in to close the ends of the box, and the said straps being adapted to pass around the wrist and to be secured in position thereon.

Signed by me this 12th day of November, 1925.

WM. M. FREEDMAN.
